UNITED STATES PATENT OFFICE.

CARL A. BRINK, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

UNWINDING DEVICE.

1,317,544.

Specification of Letters Patent. Patented Sept. 30, 1919.

Application filed December 16, 1916. Serial No. 137,408.

To all whom it may concern:

Be it known that I, CARL A. BRINK, a citizen of the United States, residing at Providence, in the county of Providence, 5 State of Rhode Island, have invented certain new and useful Improvements in Unwinding Devices, of which the following is a specification.

My invention is an improved device for 10 controlling the unwinding of yarn, thread or the like from skeins, hanks, spools or other supplies in delivering it to winding machines or similar textile apparatus. The object of my improvement is to provide 15 means for facilitating the delivery of the yarn under a uniform tension, without undue strain or breakage, and to prevent snarling, kinking or overrunning.

The manner and means for carrying out 20 the improvement are fully described in the following specification, illustrated by the accompanying drawings, in which like reference characters designate like parts. In the drawings:

25 Figure 1 is a general view of my improved device shown as applied to a swift or reel for unwinding the yarn from a skein held thereon, and illustrating a conventional form of winding machine to which the yarn 30 delivers;

Fig. 2, an enlarged view of a portion of the swift showing the method of operation of the unwinding device in connection therewith;

35 Figs. 3 and 4, enlarged, detail views of the friction-brake device for the yarn-controller;

Fig. 5, a detail view of the hub or mounting for the controller-arm;

40 Fig. 6, an enlarged, side view of the swift support or bracket showing the method of attaching the swift-spindle thereto; and

Fig. 7, an enlarged, detail, plan view of the spindle-attaching means.

45 Referring first to Fig. 1, I have here illustrated my improved mechanism as applied to use in connection with a reel or swift S, on which the skein Y is held while delivering the yarn y to a winding machine

50 W. It is to be understood, however, that the invention is applicable to other varieties of supply-holders, such as spools, bobbins, or the like, and is also adapted for use with various other types of textile apparatus. As

55 shown in Fig. 1, the winding machine W

comprises a frame or casing C, carrying bearings for the rotatable winding-spindle B and reciprocable traverse-rod D, and enclosing the mechanism M for operating the same. On the traverse-rod D is a 60 thread-guide G to which the yarn is delivered to be wound onto the bobbin b held on the spindle B. With this type of machine it is the usual practice to mount the swift S above the winding-spindle B in convenient position for leading the yarn down from the skein Y to the guide G. For this purpose one or more A-shaped uprights E are fastened to the top of the machine frame or casing C and arranged to support a horizontal rod e at the top. The rod e serves as a support for a series of arms or brackets F which are clamped to its sides and extend angularly therefrom to provide bearings for the swifts S. 70

Usually the machine frame C carries a plurality of winding-spindles B, spaced along its opposite sides, and a bracket or arm F is provided for each spindle. Each bracket F is constructed with a hub f at 80 its outer end formed with a slot f' for receiving the spindle s on which the swift S rotates, see Figs. 2, 6 and 7. As shown more particularly in Figs. 6 and 7 the spindle s simply rests in the slot f' and is 85 held fixedly in place by means of a clamping-lever L. The lever L is preferably constructed of sheet-metal in the form of a handle l having a crook l' at its end. The end of the crook l' is pivoted on a stud m 90 screwed into the side of the arm F. The end of the spindle s is arranged to project beyond the side of the hub f on the arm F and is formed with an annular, beveled groove s' with which the lever L engages. 95 Preferably the edge of the lever L is beveled or rounded off to adapt it to fit snugly into the groove s' and, as shown in Fig. 6, the under side of its crook l' is of such form as to adapt it to dog against the spindle s. That is to say, when the spindle s is inserted in the slot f' and the lever L turned down to engage with its groove s' the eccentric curvature of its engaging edge will cause it to clamp the spindle securely 100 in its bearing.

In Fig. 2, I have illustrated a familiar type of reel or swift S which is constructed with radially contractible arms or spokes a to facilitate the placing of the skein thereon 110

and to render it adjustable therefor. At the outer ends of the arms a are fork-like cross-members a' over which the skein Y is stretched. Any other form of swift, reel or support for the yarn may be employed in the place of the one here shown, however, and it is to be understood that my present improvement is independent of this part of the apparatus. As shown in Fig. 2 the hub h of the swift S is bored at h' to adapt it to receive the spindle s on which it rotates, and usually its turning movement is controlled by a friction-brake. This, in its simplest form, may consist merely of a band 10 or strap k looped around the concaved end of the hub h and arranged to suspend weights w strung on a rod or pin p . The weights w cause a slight friction or drag of the band k on the hub h and thereby serve 15 to resist the turning movement of the swift to control its rotation in the usual manner.

My improved controlling device for regulating the unwinding of the yarn y from the skein Y is mounted on the outer end of the spindle s , beyond the hub h of the swift S , and serves a further purpose in retaining the swift in place on the spindle. As shown most clearly in Fig. 2, it comprises a controller-arm X supported by a hub R to rotate about the axis of the swift S , and controlled in its movement by a friction-brake V . Referring particularly to Fig. 5, the hub R is formed with a longitudinal bore r 20 extending throughout the greater portion of its length, and with an enlarged annulus r' at one end. The annulus r' is formed with flanges 2—2 to provide a peripheral groove or seat for receiving the braking element V held thereagainst by a tongs-member T , see Fig. 3. The hub R is also scored with an annular groove 3 providing the relatively thin flange 4 at its end.

As shown in Fig. 3 the tongs-member T 25 is mounted on a harp-shaped support U constructed from sheet-metal as illustrated in Fig. 4. The upper part of the member U is divided by the vertical slits u , u and the portion of the metal cut away at the center is bent back in the offset arm u' , see Fig. 2. At its upper end the arm u' is perforated 30 with a "button-hole" opening or slot 5 having its larger, circular portion 6 of a diameter to adapt it to fit freely over the outside of the spindle s . Referring now to Fig. 5, the spindle s is slotted at 7, 7 on its opposite sides to provide a flattened portion with which the relatively narrow opening 8 of the button-hole 5 engages as shown in Fig. 4. Referring more particularly to Fig. 2, the cutting away and bending back of the arm u' leaves two prongs 9—9 extending upwardly from the lower portion of the member U and these are adapted to straddle the hub R to 35 engage with its peripheral groove 3.

Through this construction and arrangement of the member U the hub R is held in place on the spindle s while allowing it to rotate about the axis thereof, in the manner as more fully explained hereinafter.

As illustrated in Fig. 3 the tongs-member T is constructed from a flat strip of sheet-metal bent in U -shape at the bottom with its opposite, parallel arms t , t bowed out at the top to partly encircle the brake-member or flanged annulus r' on the hub R . Inserted between the arcuate ends of the arms t , t and the brake-member r' is the friction element or brake-lining V which may be a strap of leather, felt or other suitable material. 40 The tongs T is supported on the harp-member U , as before mentioned, by bending it around a slotted finger or lug 10 projecting at right-angles from its lower end, see Figs. 2 and 3. A thumb-screw J extends through 45 openings in the arms t , t and is screwed into a flat nut or washer j on one side thereof. By turning up the screw J the tongs is clamped against the lug 10 on the supporting-member U and the curved ends of its arms t , t are caused to hold the brake-band V against the brake-annulus r' with more or less pressure as required.

At the outer end of the hub R is an enlargement 11 formed with a transverse bore 12 in which is secured the controller-arm X . Preferably the arm X is constructed from relatively thin tubing, to render it light in weight, and inserted in its outer end is a wire extension X' which may be soldered or secured thereto in any suitable manner. The wire X' is bent into a loop or eye x adjacent the side of the cross-member a' of the swift S and thence extends to a point opposite the center of the swift where it is formed with a second eye x' . From the eye x' the wire extends outwardly in a guard-finger x^2 overhanging the opposite side of the swift S . Inserted through the hole 12 in the hub R is a wire arm 14 carrying a disk-shaped weight 15 at its outer end, see Fig. 2. A set-screw 16 in the hub R serves to bind the butt end of the arm X and the end of the wire 14 in place in the hole 12 and the weight 15 acts as a counterbalance for the controller-arm. As illustrated in Fig. 2 the hub R is turned down at its outer end and scored with screw-threads forming a stud-like projection 17. Wound about the threads of the stud 17 is a wire 18 terminating in a loop or pigtail 19.

Having now described the construction and arrangement of the parts of my new device, its method of operation will next be explained: In assembling the mechanism the tongs T is clamped to the member U , as shown in Fig. 3, with its upper end embracing the brake-annulus r' to press the brake-band V thereagainst. In this position the sides or prongs 9—9 of the member U en-

gage the groove 3 of the hub R and the arm u' lies adjacent its flanged end as shown in Fig. 2. By releasing the thumb-screw J the harp-member U may be slid longitudinally 5 in relation to the tongs T and to apply the hub R to the spindle s the enlarged end 6 of the button-hole-slot 5 is brought down opposite the bore r in the hub. With the opening 6 registering with the bore r the end of 10 the spindle s is inserted therethrough until the slots 7-7 come into alinement with the arm u' . The member U is then pushed up into the position illustrated in Fig. 4 to engage the sides of the narrow portion 8 of its 15 button-hole 5 with the slots 7-7, and in this manner the member U and tongs T are held from turning on the spindle s. The thumb-screw J is now tightened to cause the arms t, t to press their brake-lining V against the 20 annulus r' to the required degree to apply a slight resistance to the turning of the hub R on the spindle s. At the same time the prongs 9-9 serve to hold the hub R in place on the spindle to allow for its rotation when 25 the controller-arm is turned clockwise about its axis.

In preparing the yarn for delivery the skein Y is stretched around the cross-member a' of the arms or spokes a of the swift S 30 in the usual manner, as illustrated in Fig. 1, and this is most easily accomplished before the swift is mounted on its bearing. After the skein is in place on the swift S the spindle s is inserted through the bore h' in 35 its hub h with the arm u' abutting the outer end thereof as shown in Fig. 2. The end of the spindle s is then seated in its slot j' at the end of the bracket F and the lever l brought down into engagement with its 40 groove s' to clamp it in place. For some uses the spindle s might be secured permanently to the bracket F and the swift S applied to or removed therefrom by detaching the hub R and its associated fastening- 45 means. In most instances, however, it is necessary to arrange the swifts in closely-adjacent relation in order to accomodate the greatest possible number within a limited space. With space an important factor, 50 therefore, I have provided the herein described arrangement for disconnecting the spindle itself from its bracket or support F in order to allow for the removal of the swift S without interference with its neighbors. That is to say, with the present arrangement the swift may be taken down from and replaced in its bearings without necessitating sliding it off from the end of 55 its spindle.

With the parts of the apparatus assembled as shown in Figs. 1 and 2 the free end of the 60 yarn y is threaded through the eye x' on the controller-arm X, next through the eye x and thence led down through the axially-ar- 65 ranged pigtail 19. From the pigtail 19 the

yarn leads to the thread-guide G of the winding machine W and thence to the winding-spindle B on which it is to be coiled. When the winding-machine or other apparatus which takes up the yarn is first started 70 there will be a sudden pull or draft on the yarn which is liable to strain or break the material before the reel or swift S can be started to unwind the skein Y. That is to say, the inertia of the swift, which is considerable as compared to the strength of fine silk yarns or other delicate materials, must first be overcome before the yarn can be delivered freely from the skein. With my present improved apparatus the sudden pull 75 and strain on the yarn is compensated for by the movement of the controller-arm X. The arm X being free to turn on the axis of the swift and being relatively light and delicately balanced it requires very little force 80 to move it. Therefore, as the yarn is taken up by the draft on the machine to which it is delivering a sudden pull will first initiate a turning movement of the arm X to pay the 85 yarn off from the skein Y. The guide-eye x' at the end of the arm X being spaced a slight distance away from the periphery of the swift S also adapts it to lift the yarn off from the skein and to free it from entanglement with the coils thereof. In this manner 90 the controller-arm operates somewhat like the human action of the arm and fingers in unwinding from a skein while easing the free length off therefrom. After the machine commences to take up the yarn with a 95 steady draft the reel S will be started to rotate to unwind it from the skein, slowly at first but with a gradual acceleration while the turning movement of the controller-arm X is continued, but at a slower rate. In case 100 the yarn meets with any obstruction in its delivery from the skein, however, the arm X will immediately start to move at a faster rate if the swift is held from turning. Another important feature of my improved de- 105 vice results from its control over the yarn when its draft is discontinued. In taking off the yarn at a high rate of draft the swift S will attain a considerable speed with consequent appreciable momentum. Now, when 110 the machine to which the yarn is delivering is stopped for any reason, the swift will have a tendency to continue to rotate to give off more yarn than required. Under this condition, when the draft on the yarn ceases, 115 the controller-arm X immediately comes to rest and if the swift S continues to run ahead the yarn will simply be wound back on the skein Y. Now, when the machine is started again the controller-arm will turn 120 back to take up this overrun and will then reverse its motion until the swift starts to rotate again under the normal draft. In this way a very sensitive and active control 125 is maintained over the yarn during its un- 130

winding, with all unequal resistance to delivery compensated for by the movement of the arm X, thus preventing undue strain or breakage. Through this equalizing control 5 the ultimate tension on the delivering yarn is maintained more even and uniform and hence the cop, bobbin or other package being wound from the skein is improved in quality. In other words, the cop or bobbin being 10 produced is wound under more uniform tension, without strain or breakage of the yarn, and hence will deliver more freely and uniformly in unwinding, thereby improving the quality of the cloth or other ultimate product for which it is intended.

My new device is extremely compact and simple in construction and particularly efficient for the purpose intended. It also provides for convenient application of the 20 supply to its holder in position for delivery to the machine and easily accessible for piecing up the ends. Various modifications might be made in the form and construction of the parts of my improved device without 25 departing from the spirit or scope of the invention; therefore, without limiting myself to the exact embodiment shown and described, what I claim is:—

1. In an unwinding device for controlling 30 the delivery of yarn, thread or the like from rotating supplies, the combination with a dead-spindle, of a supply-holder rotatably mounted thereon, a hub rotatably mounted on the end of the spindle, an arm adapted to 35 be fixedly attached at one end to the spindle to prevent its rotation thereabout, a braking-member mounted on said arm and provided with spring-elements straddling the periphery of the hub to apply frictional 40 resistance to its rotation, and a controller-arm extending radially from the hub and carrying yarn-guiding means at its end for leading the yarn off from the supply.

2. In an unwinding device for controlling 45 the delivery of yarn, thread or the like from rotating supplies, the combination with a dead-spindle, of a supply-holder rotatably mounted thereon, a hub rotatable on the spindle, an arm rigidly engaged with the 50 spindle and extending radially therefrom, a resilient brake-member mounted on the end of the radial arm with its inner end bearing against the hub to apply frictional resistance to the rotation thereof, and a controller-arm 55 extending radially from the hub and carrying yarn-guiding means at its end for leading the yarn off from the supply.

3. In an unwinding device for controlling 60 the delivery of yarn, thread or the like from rotating supplies, the combination with a dead-spindle formed with slots in its sides, of a supply-holder rotatable on the spindle, a hub rotatable on the spindle, a radial 65 braking-arm having means engaging the slots in the spindle to attach it fixedly

thereto, a brake-member mounted on the radial member to adapt it to bear frictionally against the hub, and a controller-arm extending radially from the hub and carrying yarn-guiding means at its end for leading the yarn off from the supply.

4. In an unwinding device for controlling the delivery of yarn, thread or the like from rotating supplies, the combination with a dead-spindle, of a supply-holder rotatable 70 thereon, a hub rotatable on the spindle, a member rigidly engaged with the spindle and extending radially therefrom, a tongs-member supported at the outer end of the radial member and provided with spring- 80 arms engaging the periphery of the hub to apply frictional resistance to its rotation, and a controller-arm extending radially from the hub and carrying yarn-guiding means at its end for leading the yarn off 85 from the supply.

5. In an unwinding device for controlling the delivery of yarn, thread or the like, the combination with a fixed bracket, of a spindle, means for detachably securing the end 90 of the spindle to the bracket, a supply-holder rotatable on the spindle, a radial braking-arm adapted to be detachably secured to the outer end of the spindle to prevent its rotation thereon, a brake-hub rotatable on the spindle, braking-means carried by the radial arm and engageable with the hub to control its rotation, and a controller-arm extending radially from the brake-hub and carrying yarn-guiding means at its end 95 rotatable about the periphery of the supply-holder.

6. In an unwinding-device, the combination with a bracket having a slotted bearing, of a dead-spindle engageable with said bearing and formed with an annular groove at its end, a lever pivoted on the bracket to adapt its edge to be engaged with the groove in the spindle to secure the latter in position, a supply-holder rotatable on the spindle, 105 and a controller-arm rotatably mounted on the spindle and carrying yarn-guiding means 110 at its end.

7. In an unwinding-device, the combination with a dead-spindle having slots in its 115 sides, of a harp-member having an arm formed with a button-hole opening adapted to slide over the spindle to engage its sides with the slots therein, a hub rotatable on the end of the spindle and formed with an annular groove with which the forked sides of the harp-member engage to retain it longitudinally in place on the spindle, and a yarn-controlling arm carried by said hub.

8. In an unwinding-device, the combination with a dead-spindle, of a brake-hub rotatable thereon and formed with an annular groove, a harp-member engaging slots in the sides of the spindle and formed with forked prongs engaging the groove in the brake- 125 130

hub, and a tongs-member mounted on the harp-member with its arms encircling the periphery of the hub to apply frictional pressure thereto.

- 5 9. In an unwinding-device, the combination with a dead-spindle, of a brake-hub rotatably mounted thereon, a member rigidly attached to the spindle and extending radially therefrom, a tongs-member supported

on the radial member and arranged with its 10 opposite arms engaging the periphery of the hub, and an adjusting-screw extending through the arms of the tongs-member to regulate its pressure against the sides of the hub.

15

In testimony whereof I affix my signature.

CARL A. BRINK.
